Hartford, Conn. 06114

Filed Feb. 1, 1967, Ser. No. 5,650

Term of patent 14 years

(Cl. D44—29)

FIG. 1

FIG. 2

FIG. 3

FIG. 4

FIG. 1 is a perspective view of a hand gripper for holding fish embodying my novel design.

FIG. 2 is a top plan view thereof.

FIG. 3 is a bottom plan view thereof.

FIG. 4 is an elevational side view of said hand gripper for holding fish shown with its forward end inclined slightly upwardly.

FIG. 5 is a front elevational view thereof.

FIG. 6 is a rear elevational view thereof.

FIG. 7 is a side elevational view of my novel hand gripper for holding fish shown in an open condition, in carrying position, as it would be suspended from a fisherman's belt.

FIGS. 2-7 are drawn to a slightly larger scale than that of FIG. 4.

I claim:

The ornamental design for a hand gripper for holding fish, as shown and described.
